United States Patent Office

Des. 193,792
Patented Oct. 9, 1962

193,792

CLIMBING TYPE PLAY DEVICE

Frank J. Stefe, Milwaukee, Wis., assignor to Safway Steel Products, Inc., Milwaukee, Wis., a corporation of Wisconsin

Filed Feb. 23, 1962, Ser. No. 68,926

Term of patent 14 years

(Cl. D34—5)

The single FIGURE is a perspective view of a climbing type play device showing my new design, the opposite side being substantially a mirror image thereof.

The essential features of my design reside in the portions shown in full lines.

I claim:

The ornamental design for a climbing type play device, as shown in the drawing and as described.
